UNITED STATES PATENT OFFICE.

MARGUERETTE ELIZABETH PURDY, OF RIDGEFIELD PARK, NEW JERSEY.

COMB.

941,586.

Specification of Letters Patent. Patented Nov. 30, 1909.

Application filed October 13, 1908. Serial No. 457,585

To all whom it may concern:

Be it known that I, MARGUERETTE E. PURDY, a citizen of the United States, residing at Ridgefield Park, in the county of Bergen and State of New Jersey, have invented a new and useful Comb, of which the following is a specification.

This invention relates to combs of that general class employed by women in dressing and arranging their hair and has for its object to provide a comparatively simple and inexpensive device of this character in which the comb is positively locked against accidental displacement.

10 A further object is to provide a comb having a laterally movable section associated therewith and provided with upwardly extending teeth adapted to interlock or mesh with the teeth or tines of the comb thereby to retain the latter in position in the hair.

15 A further object is to provide the movable section with a laterally curved or bowed portion which forms a housing for the teeth of the same so that the device will have the 20 appearance of an ordinary comb.

A still further object of the invention is generally to improve this class of devices so as to increase their utility, durability and efficiency as well as to reduce the cost of 25 manufacture.

30 Further objects and advantages will appear in the following description, it being understood that various changes in form, proportions and minor details of construction 35 may be resorted to within the scope of the appended claims.

In the accompanying drawings forming a part of this specification: Figure 1 is a perspective view of a comb constructed in accordance with my invention and showing the application of the same. Fig. 2 is a front elevation of the comb detached. Fig. 3 is a transverse sectional view taken on the line 3—3 of Fig. 2. Fig. 4 is a top plan view showing the movable section or auxiliary comb in open position. Fig. 5 is a similar view showing the auxiliary comb in closed or operative position. Fig. 6 is a rear elevation partly in section of a portion 50 of the movable section or auxiliary comb.

Similar numerals of reference indicate corresponding parts in all of the figures of the drawings.

55 The improved device comprises a main comb section or body portion 5 formed of

gutta-percha, celluloid, tortoise shell or other suitable material having an inherent flexibility, said comb being of any suitable size and shape and provided with a plurality of spaced tines or teeth 6.

Secured to and preferably formed integral with one of the end teeth or tines 7 is a movable section or auxiliary comb 8, the latter being preferably in the form of a horizontally disposed bar which extends longitudinally of the comb at the upper edge thereof and is curved to conform to the general contour or outline of the comb, as shown.

70 The auxiliary comb or bar 8 is curved or bowed outwardly, as indicated at 9 and molded or otherwise formed on the lower edge of said bar are a plurality of spaced upwardly extending teeth 10 adapted to interlock or mesh with the teeth or tines 6 of the main comb section and thus prevent accidental displacement of the main comb when the latter is in position in the hair.

75 The free end of the auxiliary comb or bar 8 is normally and yieldably supported in spaced relation to the adjacent end of the main comb section so as to permit the latter to be readily positioned in or removed from the hair when desired, said section being 80 supported in spaced relation to the body portion by the inherent flexible properties of the tortoise shell or other material of which the body of the comb is formed.

85 One end of the main comb section 5 is provided with an opening in which is seated a spring socket 11 adapted to receive an enlarged head or knob 12 formed on the adjacent end of the auxiliary comb section 8 thereby to lock the auxiliary section in engagement with the main comb after the latter has been placed in position in the hair.

90 Attention is called to the fact that the auxiliary comb or bar 8 forms a housing or casing for the teeth 10 so that the device 95 will have the appearance of an ordinary comb. It will also be observed that by having the central portion of the bar 8 curved outwardly the free ends of the teeth are spaced from the interior walls of the bar 100 and are thus free to intermesh with the teeth or tines on the main comb section, and in position to engage the hair so as to prevent accidental displacement of the comb after the auxiliary section has been moved 105 to closed or operative position.

110 In using the device the comb is inserted

in the hair either at the front or back of the head and the auxiliary section or bar 8 moved to closed position and locked in engagement therewith by introducing the head 12 into the spring socket 11. With the comb in this position it will be seen that any upward movement of the main comb section will cause the teeth 10 to engage the hair and act as a stop to prevent further movement thereof. In order to remove the comb it is merely necessary to disengage the head or knob 12 from the socket 11 when the spring action of the auxiliary bar or section 12 will automatically move the same to open position thus disengaging the teeth 10 from the tines 6 and permitting removal of the comb.

While a resilient socket and head is preferably employed for retaining the main and auxiliary comb sections in locked position it is obvious that any other suitable form of fastening device may be employed for this purpose.

From the foregoing description it will be seen that there is provided an extremely simple, inexpensive and efficient device admirably adapted for the attainment of the ends in view.

Having thus described the invention what is claimed is:

1. A device of the class described including integral main and auxiliary comb sections, the teeth on the auxiliary comb section being extended upwardly and arranged to mesh with the teeth on the main comb section.

2. A device of the class described including main and auxiliary comb sections one of which is yieldably supported on the other and provided with upwardly projecting

teeth, and means for locking said comb sections in engagement with each other.

3. A device of the class described including a main comb having an auxiliary comb formed integral therewith and extended longitudinally of the main comb at the upper end of the latter, the teeth on the auxiliary comb being extended upwardly from the lower longitudinal edge thereof, and means for locking said combs in engagement with each other.

4. A device of the class described including a main comb, an auxiliary comb formed integral therewith and having one end thereof normally and yieldably supported in spaced relation to the main comb, the teeth on the auxiliary comb being extended upwardly and arranged to intermesh with the teeth of the main comb, and an enlarged head formed on the free end of the auxiliary comb and adapted to enter a corresponding socket formed in the adjacent end of the main comb.

5. A device of the class described including a main comb, an auxiliary comb formed integral therewith and having its central portion bowed outwardly and its lower longitudinal edge provided with a plurality of spaced upwardly extending teeth adapted to intermesh with the teeth on the main comb when the auxiliary comb is moved to closed position, and means for locking the main and auxiliary combs in closed position.

In testimony that I claim the foregoing as my own, I have hereto affixed my signature in the presence of two witnesses.

MARGUERETTE ELIZABETH PURDY.
